ABSTRACT: A cleaning and polishing cloth consists of a cotton fabric impregnated with mineral spirits. It is made by washing and drying a piece of cotton material, immersing it into a bath of mineral spirits, then wringing it and then allowing it to dry for a period of about 5 to 7 days. The finished cloth may be sprayed with perfume, if desired. It can be used most effectively for cleaning and polishing all types of articles, as well as a floor mop and a blackboard wiper.

CLEANING AND POLISHING CLOTH AND METHOD OF MAKING IT

This invention relates to a cleaning and polishing cloth and a method of making it.

An object of the present invention is the provision of a cloth of this type which is most inexpensive to manufacture and which is most effective for industrial as well as domestic uses, namely, for cleaning and polishing a variety of articles, including its use as a floor mop and a blackboard wiper.

Other objects of the present invention will become apparent in the course of the following specification.

In accomplishing the objectives of the present invention it was found that a pure cotton fabric must be used. However, the type and the texture of the cotton fabric were found to be immaterial for the purposes of the present invention, in fact the least expensive cotton fabrics were found to provide the best results.

The basic feature of the present invention consists in that the piece of cotton fabric is impregnated with mineral spirits. The term "mineral spirits" defines a preparation which is well known and is sold to the general public. It consists of a specific mixture of the following specific ingredients:

Naphthalene (tar camphor, $C_{10}H_8$)	41%
Paraffin (C_nH_{2n+2})	43%
Aromatic benzene (C_nH_6)	15.9%
Sulfur	0.1%

The process of the present invention consists essentially in that a cotton fabric is cut to pieces of desired size which are then washed and dried, passed through a bath of mineral spirits, then squeezed and finally allowed to dry for a lengthy time period of about 5 to 7 days. The cleaning cloths are then ready for use. However, since they have a slight odor to which some users might object, it is advisable to spray them with any suitable perfume.

The following example is given by way of exemplification only:

EXAMPLE

A length of cotton fabric is cut into pieces of suitable size. Pieces measuring 12 inches by 9 inches may be used, since this size was found to be most satisfactory. However, obviously, pieces of a large variety of sizes can be used. The pieces are preferably provided with sewn edges. The completed pieces are washed in a suitable washing machine and then dried. It is advisable to use any suitable fluffy compound during the washing to make the pieces soft.

Then the pieces are immersed into a bath of mineral spirits

50

and allowed to stay there until fully impregnated. Then they are removed from the bath and passed through a squeezing apparatus, such as a wash-ringer. The squeezed out pieces are allowed to dry in open air, for example, by being hung on a wash line. The drying period amounts to about 5 to 7 days.

The amount of mineral spirits consumed during the process depends obviously upon the amount of treated pieces of fabric. It was determined from practical experience that when 33 pieces of the described size were treated jointly in 1 quart of mineral spirits, the consumption of mineral spirits amounted to only 4 percent.

After the cloths are dried, they are ready for use. However, since they do have a certain odor which may be found unpleasant by some users, it is advisable to spray them with any suitable perfume and pack them in cellophane bags.

Cloths made in accordance with this process were found to be of outstanding quality. They can be used in homes for cleaning and polishing all kinds of household articles, including silverware, tableware, china, ornamental articles and furniture. Cloths of larger size can be used as floor mops. In schools, they can be used for cleaning blackboards. In industrial works, they can be used for cleaning various industrial equipment. A further advantage of these cloths is that they can be guided over hot surfaces without burning or being damaged.

I claim:

1. A cleaning and polishing cloth consisting of a piece of cut and dry cotton fabric impregnated with a preparation consisting of

naphthalene (tar camphor $C_{10}H_8$)	41%
paraffin (C_nH_{2n+2})	43%
aromatic (benzene C_nH_6)	15.9%
sulfur	0.1%

2. A cloth in accordance with claim 1, wherein said piece has sewn edges.

3. A method of making a cleaning and polishing cloth, comprising providing a cut piece of cotton fabric, washing the fabric, drying the fabric, impregnating the fabric with a preparation consisting of

naphthalene (tar camphor $C_{10}H_8$)	41%
paraffin (C_nH_{2n+2})	43%
aromatic (benzene C_nH_6)	15.9%
sulfur	0.1%

45 squeezing the impregnated fabric and then drying the squeezed fabric.

4. A method in accordance with claim 3, wherein the dried fabric is sprayed with perfume.
